UNITED STATES PATENT OFFICE.

ELWIN I. SHELDON, OF GREENWOOD, WISCONSIN, ASSIGNOR OF ONE-HALF TO AUGUST BAUMANN, OF GREENWOOD, WISCONSIN.

FLUE-STOPPER.

No. 866,526.

Specification of Letters Patent.

Patented Sept. 17, 1907.

Application filed March 3, 1906. Serial No. 304,030.

To all whom it may concern:

Be it known that I, ELWIN I. SHELDON, a citizen of the United States of America, residing at Greenwood, in the county of Clark and State of Wisconsin, have 5 invented new and useful Improvements in Flue-Stoppers, of which the following is a specification.

This invention relates to improvements in flue stoppers of that kind provided with a closure plate adapted to cover the flue opening, the object of the invention 10 being to provide a simple and effective device of this nature provided with means for securing it in applied position and for receiving the dirt or soot which is ordinarily deposited in the flue opening and is liable to fall within the room or compartment when the 15 stopper is removed preparatory to inserting a stove pipe within the flue opening.

In the accompanying drawings,—Figure 1 is a vertical section through a flue and stopper embodying my invention. Fig. 2 is a rear perspective view of 20 the stopper. Fig. 3 is a section on line 3—3 of Fig. 2.

Referring to the drawings, 1 designates a flue and 2 the flue opening or passage formed in the wall 3.

The stopper comprises a closure plate 4 having a substantially flat central portion 5 and a rearwardly 25 curved or bent rim 6 provided with a flat flange 6^a. The plate 4 closes the outer end of the flue opening 2 with its flange 6^a bearing in the usual manner against the face of the wall 3 around the opening. Carried by the plate is a pan or receptacle 7, preferably of 30 substantially semi-circular form and closed at its rear end by a wall 8. The forward end of said pan or receptacle is normally open and closed by the central portion 5 of the plate. The pan or receptacle extends rearwardly from the plate and rests upon the bottom 35 of the flue opening to catch the dirt or soot deposited therein from the flue. The forward end of the pan may be fastened to the plate in any preferred manner, but is preferably secured thereto by providing the front edge of the pan with a flanged portion 9 to bear 40 against the plate, said flanged portion being slit at intervals and parts thereof displaced to form tongues 10 which project through slits or openings 10^a in the plate and are clenched upon the outer face thereof to firmly fasten the plate in position. The peculiar for- 45 mation of the plate described provides an annular shoulder 11 against which the flanged end of the pan bears, the shoulder forming a seat to more firmly and securely hold the pan in applied position.

A spring 12 consisting of a looped piece of spring

wire is employed for holding the stopper in operative 50 position. This spring has its central portion bowed upwardly to bear against the upper wall of the flue opening 2 as at 12^a and is suitably secured at its forward end to the plate, as indicated at 13. The rear end of the spring is downwardly and forwardly curved, 55 as at 12^b, and projects into the pan through an opening 14 formed in the rear wall thereof, the wire being loosely movable in said opening in order to permit the spring to adjust itself to the size of the passage 2 and bear with the required force against the wall there- 60 of. The free end 12^b of the spring terminates within the body of the pan and is upwardly bent or curved to extend on a proper arc with the portion 12^b to permit the latter to be properly movable through the opening 14, and such construction of the spring also 65 causes an upward pressure to be exerted by the portion 12^a against the upper wall of the opening 2, by which the pressure of the spring and the weight of the pan resting on the bottom wall of the opening serve to hold the device in position. By mounting the part 70 12^b to slide freely in the opening 14 provision is made to permit the spring wire to be bent to vary the form of the bow or loop so that the pressure of the part 12^a may be increased or diminished, as will be readily understood. The spring also serves the additional 75 function of a handle, whereby when the stopper is removed it may be conveniently transported.

The operation of the device will be readily understood, and it will be seen that as the greater porportion of the dirt and soot deposited in the flue passage 80 2 will be caught by the pan 7, the removal of such portion of the deposits will be cleanly effected when the stopper is detached, thus preventing the objection previously stated.

Having thus described the invention, what is claimed 85 as new, is:—

1. A flue stopper comprising a closure plate, a receptacle extending rearwardly therefrom, said receptacle being open at the top and closed at its front end by the plate and provided with a rear wall having an opening 90 in the upper portion thereof, and a bowed spring arranged above the pan and fixed at its forward end to the plate, the rear end of said spring being extended forwardly and loosely through the opening in the said rear wall of the pan and bent upward at its extremity to exert an upward 95 spring tension.

2. A flue stopper comprising a closure plate having a substantially flat central portion, and a rearwardly curved rim terminating in a flat bearing flange, an annular shoulder being formed at the juncture of said central 100

portion and rim, an open-topped pan extending rearwardly from the closure plate and provided with a rear wall having an opening therein and an open front end, the latter being closed by the flat portion of the plate, the body of the pan bearing at its forward end against said shoulder and being provided with a flange abutting against the flat portion of the plate and provided with fastening tongues extending therethrough, and a bowed spring fastened at one end to the flat portion of the plate above the

pan and extending above and in rear of the latter and 10 having its other end inturned and loosely projecting through the opening in the rear wall of the pan.

In testimony whereof, I affix my signature in presence of two witnesses.

ELWIN I. SHELDON.
